UNITED STATES PATENT OFFICE.

THOMAS SPENCER MILLER, OF SOUTH ORANGE, NEW JERSEY.

LOAD-TRANSFERRING DEVICE.

SPECIFICATION forming part of Letters Patent No. 674,539, dated May 21, 1901.

Application filed April 2, 1900. Serial No. 11,068. (No model.)

To all whom it may concern:

Be it known that I, THOMAS SPENCER MILLER, a citizen of the United States, and a resident of South Orange, in the county of Essex and State of New Jersey, have invented a new and Improved Load-Transferring Device, of which the following is a full, clear, and exact description.

My invention relates to an improvement in devices for transferring loads from one point to another or for transferring them from one vehicle to another; and, broadly speaking, it consists of a trackway and transferring mechanism thereon in combination with a load-carrier having a load-releasing device, said trackway being inclined relative to the load-receiving and delivering points, so that the load-delivering point is farther from the trackway than is the load-receiving point, the load-releasing device being connected with the trackway-traveler and brought into action by a sufficient descent of the load.

My invention further consists of certain novel parts and combinations of parts, which will be particularly pointed out in the claims.

In the accompanying drawings I have shown my invention embodied in the form at present preferred by me; but it will be understood that various modifications and changes may be made without departing from the spirit of my invention and without exceeding the scope of the claims.

Reference is to be had to the accompanying drawings, forming a part of this specification, in which similar characters of reference indicate corresponding parts in all the figures.

Figure 1 is an elevation showing my device in use for transferring cane or similar material from a wagon to a car. Fig. 2 is a perspective view showing the arrangement of the parts which immediately support the load. Fig. 3 is a detail showing the trip connection or hook by which one end of the slings is connected with the load-carrier, and Fig. 4 shows this block in its opened or released position.

It is often necessary to transfer material of various kinds from one point to another adjacent thereto, and it is desirable to be able to automatically dump the material being carried at one or more predetermined points. This result has heretofore been attained by using a trip or load releasing rope or by using

a fixed stop to engage the trip. This result is attained in the invention herein illustrated by connecting the trip with the trackway traveler or carriage, so as to automatically release the trip when the load is lowered to a certain distance beneath the carriage, which may be called the "tripping" distance, and by arranging the trackway relative to the loading and releasing positions, so that in the loading position the load is nearer the carriage than this tripping distance and the load-receiver farther than this tripping distance.

I have herein shown the device as being in use for transferring cane from a wagon to a car; but it is obvious that the device may be used for transferring any kind of material, and I do not therefore wish to be limited to its use for the particular purpose herein shown and described, said purpose being given simply as an illustration of one of its uses.

My device is designed for use in connection with hoisting and conveying mechanisms of that character which are capable of raising the load at one point, conveying the same to another point, and there lowering it. The particular conveying mechanism used for producing the above operations is immaterial. I have herein illustrated a particular form of mechanism for securing the above result, but wish it understood that I do not limit myself to this form only, as any equivalent type may be employed instead. A form of hoisting and conveying mechanism adapted for this use is shown in my application, Serial No. 35,006, filed October 31, 1900.

The following is a description of the structures illustrated in the drawings:

In Fig. 1 a frame consisting of uprights A and cross beams or braces A' is shown, said frame carrying a trackway B, which is herein shown as consisting of two channel-bars slightly separated, the lower flanges of said bars being used as a surface for supporting the wheels E' of the carriage E. The trackway may, however, be made of various other forms, either as rigid bars or as a suspended cable. The trackway, as herein shown, is inclined at such an angle that the weight of the load will prevent the carriage from moving upward upon the trackway while the load is being hoisted; but as soon as the load reaches

its uppermost position or the further hoist of the load is prevented by a stop of any kind the carriage will then be caused to travel up the incline. The carriage E has suitable 5 wheels over which the hoisting-cable I passes and wheels E' running upon the trackway B, and the carriage and trackway are provided with coöperating means by which the carriage may be made to remain stationary at prede- 10 termined points upon the trackway while the carrier is raised or lowered. In the construction illustrated stops b and F are shown over the loading and unloading positions. As this 15 type of apparatus is well known in the art and is not herein specifically claimed, a detailed description thereof is not deemed necessary, especially as a full description of the mechanism herein indicated is given in my application before mentioned, in which such 20 features are specifically claimed.

In Fig. 1 the carriage and the load-carrier suspended therefrom are shown in their load-receiving position in full lines and in their unloading position by dotted lines. The car- 25 rier herein shown is particularly designed for handling cane, and consists of a frame D, having suspending-rods d', to the upper ends of which the hoisting-cable may be connected, either directly or by means of a pulley or pul- 30 leys in the frame e. From opposite sides of this frame chains or ropes d depend. These chains or ropes are provided at their lower ends with hooks adapted to receive the slings K. One of these hooks d² may be an ordinary 35 hook, but is herein shown as a spring-hook, so that the end of the sling may not become readily detached therefrom. The other hook should be an automatic releasing-hook, and a hook of this character is shown in detail in 40 Figs. 6 and 7. This consists of three mem- 45 bers—the bars J', which are secured to the lower end of the chain d, the hook J², which is pivoted to the lower ends of said bars, and the trigger or locking device J, which is piv- 50 oted between the upper ends of the bars J' and is provided with a shoulder J³, adapted to engage one end of the hook member J² and hold it in its locked position or the position 55 shown in Fig. 6. To the trigger or locking 60 plate J is attached a chain or cable h', by pulling upon which the hook will be released, so as to free the end of the sling attached thereto. The chain h' is made a little longer than the chain d, which extends upwardly to 65 the frame D. These chains are connected by any convenient device with the carriage E, such connection being of sufficient length that there will be a slight amount of slack when the device is attached to the load. The 70 connection herein shown is of the chains h' with a bar H, which rests upon any convenient portion of the frame D. This bar is in turn connected by means of chains h with the carriage. It is evident that the chains h' or 75 such equivalents thereof as might be used might be connected directly with the carriage E, and in some cases this might be the pre-

ferred construction; but with the device illus- 70 trated the form of connection described is now preferred.

The length of the connections through the chains or ropes h and h' between the hooks and the carriage is such that it is greater than the distance from the carriage to the releasing or trip hooks J in the loading position, while 75 in the unloading position the load may be freely lowered a greater distance beneath the carriage than the length of these connections, whereby when the load has been lowered at the point where it is to be discharged, as 80 shown in dotted position at D' in Fig. 1, the said chains will be tightened, so as to trip the hooks and release one end of the slings. The cane or other material being handled will then be automatically released. 85

The trackway is herein shown as being inclined, although it is evident that my invention may be operated upon a level trackway by supplying any means for returning the carriage—as, for instance, by a counterweight 90 or a tail-rope—provided the point to which the load is transferred is sufficiently beneath the point from which the load is taken to permit the adjustment of the devices in the manner described. If a transferring device is used 95 which is capable of lowering the load at more than one point, then the load may be automatically delivered at as many points, if a sufficient lowering of the load is provided for. The proper working of the device is thus seen 100 to depend upon the ability to lower farther at the delivery-point than is needed to attach to the load at the receiving-point.

This device is especially adapted to trans- 105 fer such articles as cane from a wagon to a car or from the car to a carrier of any kind, by which it may be conveyed to the mills, for transferring cargo from boat to dock, or vice versa, and, in fact, to moving any material 110 from one given point to another given point. 110

Having thus fully described my invention, I claim as new and desire to secure by Letters Patent—

1. A load-carrier for hoisting and conveying devices, comprising a frame, a series of removable slings, means for removably sus- 115 pending the ends of said slings from the frame, the suspending means for one end of the slings containing a trip-releasing device, a bar normally carried by the frame and hav- 120 ing a normally slack connection with said trip- releasing devices, and a suspending connection with said bar which is slack in the loading position of the frame, substantially as de- 125 scribed.

2. A load-carrier for hoisting and conveying devices, comprising a frame, a series of slings, a series of manually-releasing devices for se- 130 curing one end of said slings to the frame, a series of trip-releasable devices for securing the other ends of the slings to the frame, each comprising a pivoted hook-finger and a catch therefor adapted to drop into locking posi- 135 tion, a bar normally supported by the frame,

- normally slack connections from said bar to each catch, said bar being connected with the hoisting mechanism to be supported thereby when the frame is lowered to the releasing 5 point for the load, substantially as described.
3. The combination with a hoisting and conveying device provided with mechanically-operated means for raising and lowering the load-carrier at two or more points, of a load-carrier, slings adapted to be suspended from said carrier, a trip mechanism in the connection with one end of its sling and normally slack connections from said trips to the conveying mechanism adapted to be tightened to 10 release the trips when the carrier is lowered to a certain distance, substantially as described.
4. In a hoisting and conveying device, the combination with a trackway, a carriage thereon, means for moving the carriage on 15 the trackway and a hoisting-rope suspended from said carriage, of a load-supporting frame suspended from the hoisting-rope, slings adapted to be connected with said frame and to support the load and having trip-joints or 20 releasable connections therein, and trip-actuating members connected with the carriage and actuated by the descent of the load beyond a fixed distance from the carriage, substantially as described.
5. In a hoisting and conveying device, the combination with a trackway, a carriage, means for moving the carriage along the trackway, and a hoisting-rope suspended from 25 said carriage, of a load-supporting frame suspended from the hoisting-rope, slings adapted to be connected with said frame and to support the load, detaching or trip hooks incorporated in said slings, and trip-actuating 30 members connected with the carriage and said detaching or trip hook actuated to re- 35 lease said hooks by the descent of the load beyond a fixed point, substantially as described.
6. In a hoisting and conveying device, the combination with a frame, load-supporting 45 slings adapted to be connected therewith and provided with trip-joints, of a hoisting-rope connected with the frame, a horizontally-movable guide for said hoist-rope and a connection between said trip-joints and said 50 guide for the hoisting-rope, whereby the load is automatically released when lowered to a determined distance from said guide, substantially as described.
7. In a hoisting device, the combination 55 with a hoist-rope, a guide therefor, means for moving said guide horizontally and a load engaging and carrying device supported by the hoist-rope and having a trip-joint or releasable connection with an extensible connection between said trip and guide and adapted to automatically release said trip-joint and discharge the load when lowered to a determined distance from said guide, substantially 60 as described.
8. In a hoisting and conveying device the combination with a hoist-rope, and a horizontally-movable guide-support for said rope, of a load-carrier supported by the hoist-rope and having a trip device for releasing the 70 load, and a trip-actuating member continuously connecting said trip and the movable rope-guide and operative by separation of said load-carrier and guide beyond a fixed distance.
